UNITED STATES PATENT OFFICE

146,109

DESIGN FOR A DECALCOMANIA SHEET

Edgar R. Jones and Lewis T. Lanier, Miami, Fla.;
said Lanier assignor to said Jones

Application November 21, 1945, Serial No. 123,968

Term of patent 3½ years

(Cl. D59—2)

To all whom it may concern:

Be it known that we, Edgar R. Jones and Lewis T. Lanier, citizens of the United States of America, residing at Miami, in the county of Dade and State of Florida, have invented a new, original, and ornamental Design for a Decalcomania Sheet, reference being had to the accompanying drawing, forming part thereof.

Figure 1 is a plan view of a decalcomania sheet showing our new design.

We claim:

The ornamental design for a decalcomania sheet, as shown.

EDGAR R. JONES.
LEWIS T. LANIER.
